UNITED STATES PATENT OFFICE

OSCAR J. SUNDSTRAND, OF ROCKFORD, ILLINOIS, ASSIGNOR, BY MESNE ASSIGNMENTS,
TO SUNDSTRAND CORPORATION, OF WILMINGTON, DELAWARE, A CORPORATION
OF DELAWARE

TRANSFER MECHANISM

Original application filed December 31, 1920, Serial No. 434,242. Divided and this application filed
November 27, 1925. Serial No. 71,351.

This application is a division of my application Serial No. 434,242, filed December 31, 1920, (which has since matured into Patent No. 1,626,889) upon an adding and listing machine adapted to add and print items of English currency as well as decimal items. That portion of the machine which is herein claimed is the transfer mechanism, said mechanism being of such character that it 5 may be adjusted to deal with both decimals and English currency.

In the accompanying drawings, Figure 1 is a fragmental view of the adding and printing mechanism of a machine embodying the 15 features of my invention, the machine being shown as set for decimal currency.

Fig. 2 illustrates a specimen of work done upon the machine.

Fig. 3 shows the transfer mechanism associated with the tens-shillings type bar, the parts being set for English currency.

Fig. 4 is a plan view of the series of adding pinions and a portion of the transfer mechanism.

Fig. 5 is a detail view of the adding pinion associated with the pence type bar.

Fig. 6 is a rear view of a part of the mechanism shown in Fig. 3.

Fig. 7 is a plan view of a part of the transfer mechanism.

For convenience in affording an understanding of the invention, I shall describe the same as embodied in a ten-key adding and listing machine such as is disclosed in Patent No. 1,198,487, granted September 19, 1916, to Rockford Milling Machine Co. upon an application filed by Gustaf David Sundstrand, but I would have it understood that the present invention is not limited to machines of the character illustrated in said patent. The machine herein shown comprises a platen 2 and a plurality of type bars. In the present instance there are ten type bars, but the number may be greater or less. The 40 type bar A (Fig. 4) at the extreme right is for printing a signal and has no movement. The second type bar from the right is marked A^x and carries twelve type, the uppermost type being adapted to print a character (herein 45 in the letter "D") to indicate that the ma-

chine is set to add and print decimals. The remaining type on the type bar A^x are adapted to print from 1 to 11, respectively. The type bar A^x is normally in position to print the character D. The remaining type bars 55 are designated A¹, A², A³, A⁴, A⁵, A⁶, A⁷ and A⁸, and each is provided with ten type adapted to print from naught to nine, respectively. The type bars A¹ to A⁸, inclusive, are normally in position to print ciphers.

The means for vertically moving the type bars A^x to A⁸, inclusive, from the normal or initial position to any other selected position and back again may be of any preferred character, that herein shown being generally similar to the mechanism disclosed in the before-mentioned Patent No. 1,198,487 and identical with the mechanism shown in my Patent No. 1,583,102, dated May 4, 1926. The type-bar moving means therefore need not be 60 described herein.

While various forms of adding mechanism may be employed, that herein shown comprises a series of adding pinions (Fig. 4) rotatably mounted upon a shaft 126. The pinions (of which there is one for each of the type bars A^x to A⁸, inclusive) are adapted to mesh with rack 129 formed in said type bars. The pinion 125^x that meshes with the rack of the pence type bar A^x has twelve teeth. The 75 pinions 125 that mesh with the racks of the type bars A¹ to A⁸, inclusive, each have twenty teeth.

When an item is to be added, the pinions are disengaged from the racks before the type bars are raised, as explained in Patent No. 1,198,487, and the pinions are moved into mesh with the racks just before the type bars are moved downwardly. Addition therefore occurs in the downward stroke of the type bars, the extent of the rotation of the pinions depending, of course, upon the extent of movement of said bars.

While various means for transferring or carrying from one numerical order to the next higher order may be used, that herein shown is generally similar to the carrying mechanism shown in said Patent No. 1,198,487. The carrying mechanism associated with the type bars A^x to A⁸, inclusive, 95

is substantially identical with that illustrated and described in said patent.

The extent of the downward movement of the type bars A^1 to A^8 , inclusive, is limited (except in the carrying operation) by contact of the shoulder 157 (Fig. 1) on said type bars with stop lugs 158. When an amount is to be carried from one order to the next higher order, the stop lug 158 for the type bar belonging to such higher order is withdrawn, thereby allowing that type bar to descend to the limit of its downward movement. The extent of such descent is just sufficient to turn the adding pinion for that type bar through the distance of one tooth. Each stop lug is formed on a slide 159 which is guided for horizontal reciprocation. To each slide 159 is pivoted a dog 160. All of the transfer dogs are identically similar, but in order to distinguish the dog that transfers tens of shillings to units of pounds said dog is designated 160^a in Figs. 1 and 3. Each transfer dog has a tooth 161 adapted to lie in front of a stationary locking plate 162. A spring 163 tends to hold the tooth 161 in engagement with the plate 162 and also tends to pull the dog 160 and the slide 159 rearwardly. When the tooth 161 is in engagement with the front edge of the plate 162, the stop lug 159 is in position to limit the downward movement of the corresponding type bar. When the tooth 161 is disengaged from the plate, the spring 163 pulls the dog and the slide back so that the stop lug 158 is out of the path of movement of the type bar lug 157.

In the case of the type bars A^1 and A^3 to A^8 , inclusive, the means for disengaging the tooth 161 from the plate 162 consists of two diametrically opposite lugs fixed to the pinion of the next lower order, as disclosed in said Patent No. 1,198,487. (In this embodiment of the invention, two lugs are provided, because each pinion has twenty teeth.) When the amount accumulated on a pinion reaches nine, continued rotation of the pinion as the rack descends brings one of the aforesaid lugs against the end of the corresponding dog 160, thereby depressing the dog until the tooth 161 is below the front edge of the plate 162, whereupon the spring 163 pulls the dog and the slide 159 rearwardly until the lug 158 stops against the plate 162. The lug 158 is then out of the path of the rack of the next higher order, and the latter therefore moves down far enough to turn its intermeshing pinion through the distance of one tooth.

The carrying mechanism associated with the pence type bar A^x also is identical in substance with that disclosed in said Patent No. 1,198,487, the pinion 125^x (Figs. 4 and 5) having twelve teeth and having attached to one side a lug 164 adapted when the pinion makes a complete revolution to depress the

adjacent dog 160 and thus release the units-shillings type bar A^1 to downward movement equal to the distance of one tooth, as explained in said Patent No. 1,198,487.

The carrying mechanism associated with the units-shillings type bar A^1 for moving the tens-shillings type bar A^2 is like that described in said Patent No. 1,198,487.

Since there are twenty shillings in a pound sterling, the carrying mechanism for transmitting movement from the tens-shillings type bar A^2 to the units-pounds type bar A^3 operates whenever two tens have been accumulated on the pinion 125^a (Fig. 1) for the tens-shillings type bar A^2 . Said pinion (which has twenty teeth) has attached to one of its sides ten tripping lugs (see Fig. 3). Two diametrically opposite lugs are somewhat longer than the others and are designated 164^a, the shorter ones being marked 164^b on the drawing. All of the lugs 164^a and 164^b are arranged to trip the transfer dog 160^a. When decimals are being accumulated said dog 160^a occupies a position out of reach of the lugs 164^b and within reach of the lugs 164^a, and hence is operated once for every ten teeth of the pinion 125^a. When English money is being registered the dog 160^a occupies a position farther forward so as to be operated by each of the lugs, and consequently is operated once for every two teeth of the tens-shillings pinion 125^a. The means for determining the position of the dog 160^a comprises a rock shaft 416 (Figs. 4 and 6) to one end of which is fixed an arm 417. Said arm is arranged to be swung forward by means including a setting lever (not herein shown). The shaft 416 is provided with an eccentric or crank portion 422 (Figs. 1 and 6) which engages a slotted portion of a block 423 that rests on the plate 162. A leaf spring 424 engaging the rear portion of said block holds that end of the block down on the plate 162. On the forward end of the block 423 is a lug 425 that lies in a recess 426 (Fig. 7) in the front edge of the plate 162.

When English money is being added, the block 423 is in its down position (see Fig. 3), wherein the lug 425 fills the recess 426, the front edge of said lug being then flush with the front edge of the plate 162 (see Fig. 7). The block 423 is in the vertical plane of the transfer dog 160^a. When the block 423 is down (as in Fig. 3) the tooth 161 of the dog 160^a engages the front edge of the lug 425, and therefore said dog is in position to be engaged by each of the lugs 164^a and 164^b, as a result of which the units-pounds type bar A^3 is given a carrying movement whenever two tens have been accumulated on the pinion 125^a for the tens-shillings type bar A^2 .

When decimals are to be added, the operation of the before-mentioned setting lever causes the block 423 to be raised high enough so that the lug 425 is above the path of move-

ment of the tooth 161, and consequently the spring 163 holds the dog 160^a with its tooth 161 in contact with the rear end wall of the recess 426, in which position the front end of the dog 160^a is out of the orbit of the lugs 164^b but within reach of the lugs 164^a. Accordingly the type bar A³ will be given a carrying movement whenever ten has been accumulated on the pinion 125^a for the type bar A². It will be seen that the lug 425 and the rear end wall of the recess 426 constitute two alined stops for the transfer dog 160^a.

After each carrying operation, the slide 159 and the dog 160 are restored to their normal (forward) position by any preferred means, as, for example, that disclosed in said Sundstrand Patent No. 1,198,487.

It is believed that the operation of the machine will be clear from the foregoing description, particularly when reference is made to the sample of work shown in Fig. 2. The fact that clear signals, subtotals and final totals are printed in a distinctive color has been indicated in Fig. 2 by representing such signals and totals in dotted lines. The first two items are decimal items, the next numerical imprint is the subtotal of said items, following which is another decimal item and the final total. In registering and printing these decimal items and totals, the lever 417 was in the position shown in Fig. 1. The next items on the specimen of work shown in Fig. 2 are items of eleven pence and ten pence, followed by the subtotal amounting to one shilling, nine pence, after which is an item of seventeen shillings and the subtotal amounting to eighteen shillings, nine pence. The next item is ten pounds, two shillings, ten pence, followed by the subtotal of eleven pounds, one shilling, seven pence. The next item is one of nine pounds, followed by the final total of twenty pounds, one shilling, seven pence. In printing the above-mentioned items and totals of English currency, the lever 417 was in the position shown in Fig. 3.

It will be apparent to those skilled in the art that the rigid connection herein shown between the type carriers and their respective racks or actuators is not of the essence of the invention, that other well known arrangements of the type carriers and racks or actuators may be employed, and that various changes may be made in the transfer mechanism herein illustrated without departing from the scope of the invention set forth in the appended claims.

I claim as my invention:

1. In an adding machine, a transfer member, a spring tending to move said member out of operative position, means to hold said member in operative position against the action of said spring, said means including a withdrawable stop for said member, and manipulative means for withdrawing said stop.

2. In an adding machine, a transfer member having a tooth, two alined stops adapted to be engaged by said tooth to hold the transfer member in operative position, a spring tending to draw said member rearwardly to place its tooth against either stop, and means to render the foremost stop ineffective.

3. In an adding machine, in combination, an accumulating wheel having a lug, a transfer member arranged to be engaged by said lug, means to hold said member in operative position, said means including a withdrawable stop for said member, and means for withdrawing said stop.

4. In an adding machine, an accumulating wheel having a plurality of transfer lugs of differing characteristics, and a transfer member selectively operable by said lugs.

5. In an adding machine, an accumulating wheel having a plurality of lugs of different lengths, and a transfer member shiftable into position for operation by a lug of a certain length.

6. In an adding machine, an accumulating wheel having a plurality of lugs of differing characteristics, and a transfer member shiftable into position for operation by a lug having a selected characteristic.

7. In an adding machine, an accumulating pinion having a plurality of transfer lugs, there being twice as many pinion teeth as transfer lugs, one of the transfer lugs being longer than certain of the other transfer lugs.

In testimony whereof, I have hereunto affixed my signature.

OSCAR J. SUNDSTRAND.
